TIE HOLDER

Melvin Reese Baker and Dewayne Kenneth Williams,
Anaheim, Calif.

Application March 18, 1955, Serial No. 35,101

Term of patent 14 years

(Cl. D33—8)

Fig. 2 is a view in side elevation of the same;

Fig. 3 is a top plan view of the same; and

Fig. 4 is a bottom plan view of the same.

We claim:

The ornamental design for a tie holder, as shown.
